US0D1000465S

(12) **United States Design Patent** (10) **Patent No.:** **US D1,000,465 S**
(45) **Date of Patent:** ** *Oct. 3, 2023

(54) **DISPLAY SCREEN OR PORTION THEREOF
WITH GRAPHICAL USER INTERFACE**

(71) Applicant: **Apple Inc.**, Cupertino, CA (US)

(72) Inventors: **Jay Christopher Capela**, Santa Cruz, CA (US); **Alan C. Dye**, San Francisco, CA (US); **Alexander Charles Maclean**, San Jose, CA (US); **Charles Janusz Migos**, Millbrae, CA (US); **Parthibhan Mohanraj**, Cupertino, CA (US)

(73) Assignee: **Apple Inc.**, Cupertino, CA (US)

(*) Notice: This patent is subject to a terminal disclaimer.

(**) Term: **15 Years**

(21) Appl. No.: **29/845,768**

(22) Filed: **Jul. 11, 2022**

(57) **CLAIM**

The ornamental design for a display screen or portion thereof with graphical user interface, as shown and described.

DESCRIPTION

The file of this patent contains at least one drawing photograph executed in color. Copies of this patent with color drawing(s)/photograph(s) will be provided by the Office upon request and payment of the necessary fee.

The sole FIGURE shows a display screen or portion thereof with graphical user interface showing our new design.

The peripheral dashed broken lines depict a display screen or portion thereof and form no part of the claimed design.
